UNITED STATES PATENT OFFICE.

DANIEL W. TOWER, OF GRAND RAPIDS, MICHIGAN.

REFRIGERATOR CONSTRUCTION.

1,209,080.

Specification of Letters Patent. Patented Dec. 19, 1916.

Application filed December 7, 1914. Serial No. 875,865.

To all whom it may concern:

Be it known that I, DANIEL W. TOWER, a citizen of the United States of America, residing at Grand Rapids, in the county of Kent and State of Michigan, have invented certain new and useful Improvements in Refrigerator Construction; and I do hereby declare the following to be a full, clear, and exact description of the invention, such as will enable others skilled in the art to which it appertains to make and use the same.

This invention relates to a construction especially adapted to be used with refrigerators. In refrigerators, to gain access to provisions held thereby, it has commonly been necessary to open the door to the entire provision compartment of the refrigerator permitting the escape of a large volume of cold air and the entrance of a corresponding volume of warmer air from the room, irrespective of what was to be obtained from the refrigerator. In my present construction it is proposed to provide a rack in connection either with the ice-box or the provision compartment of the refrigerator designed to hold milk and butter especially, these being articles which are most commonly put in or taken out of the refrigerator, and to so construct this rack that it will be readily and easily withdrawn from the refrigerator without the necessity of opening the large door to the provision compartment, merely opening an auxiliary door behind which said device is located, thereby permitting the escape of a relatively small volume of cold air.

It is a further purpose of this invention to construct the rack with a member which will automatically close the opening in the refrigerator when the rack is drawn out, shutting off the entrance of warm air and the escape of cold air from the refrigerator.

A still further object and purpose of the invention is to construct the rack in such manner that the cold air of the refrigerator may circulate freely around the articles held thereby.

Other objects and purposes than those specifically enumerated will be apparent as understanding is had of the construction illustrated in the accompanying drawings, in which;

Figure 1 is a perspective view of the upper part of a refrigerator equipped with my improved construction and showing it with-

drawn, said construction in this instance being located at one side of the ice-chamber. Fig. 2 is a front elevation of a modified form in which the rack is located in the provision chamber of the refrigerator. Fig. 3 is a view similar to Fig. 2, of the lower portion of a refrigerator showing the door to the provision chamber open. Fig. 4 is a side elevation of the rack and the connected extension guide therefor. Fig. 5 is a plan view thereof. Figs. 6 and 7 are a plan and a side elevation of the extension guide respectively. Figs. 8, 9 and 10 are respectively sectional views taken on the lines 8—8, 9—9 and 10—10 of Fig. 6, looking in the direction indicated by the arrows; and Fig. 11 is a fragmentary side elevation of the extension guide illustrating the method of separation of certain parts of said guide.

Like reference characters refer to like parts throughout the several views of the drawings.

The refrigerator illustrated at 1 may be of any conventional design having a provision compartment closed by the door 2 above which compartment is located the ice chamber back of the front 3. In the modification shown in Fig. 1 a small door 4 is located at one side of the front 3, back of which may be placed the rack for holding different provisions; this rack in such case lying immediately alongside the ice in the ice-box. It is not necessary, however, in the use of the invention that it shall be located at any precise spot in the refrigerator. For instance, the door 2 to the provision compartment may have at one side thereof a small door 5, similar to the door 4 above noted, back of which said rack may be located within the provision compartment as illustrated in Figs. 2 and 3. Various other possible locations may occur to others without departing from the invention.

The rack comprises in its construction a front U-shaped member having spaced apart vertical sides 6 connected by an upper cross bar 7 and a rear U-shaped member having similar vertical sides 8 connected by the cross bar 9, said rear member in all respects being similar to the front member except that it is less in height. Spaced apart horizontal bars 10 connect the vertical members 6 and 7 as shown forming a skeleton frame, the bars 10 intermediate their ends having secured thereto in any

suitable manner vertical bars 11 which serve to strengthen the frame. Cross members 12 lie between and are soldered or otherwise suitably secured to the lower ends of the members 6, 8 and 11 and beneath and attached to these cross members are the strips 13 which extend the full length of the frame forming a bottom therefor, and at their forward ends may be curved downwardly at 14 to form finger pulls by which the rack may be withdrawn from the refrigerator. Cross members 15 and 16 divide the rack into a plurality of compartments. A plurality of angle guide members 17 are located horizontally in the front compartment thus formed, being secured in any suitable manner at the inner sides of vertical members 6 and 11 and serve as supports for a plurality of shallow trays 18, each of which at its front end is provided with an extension 19 by means of which it may be manually withdrawn from the rack. In the design of this rack, the trays are shown as of a shape and separated sufficiently from each other that each may receive and hold a pound of butter in the conventional package. The rear compartments are each of such dimensions as to conveniently receive the standard bottle in which milk is ordinarily contained.

A back member 20 is detachably secured at the rear end of the rack having fastened on its front side angle members 21 and 22 which are adapted to fit over the upper and lower cross members 9 and 12, respectively, at the rear of the rack being readily removable therefrom when the back is slightly elevated. In practice the back is formed of sheet metal of slight thickness making a very light and durable construction. The rack thus constructed is mounted for slidable movement in the refrigerator, it being adapted to be contained entirely within the refrigerator or withdrawn substantially outside. To attain these ends I have secured on the underside of the rack a bar 23 connected at its ends and adjacent its middle by Z-shaped brackets 24 to the cross members 12 of the rack. Slidably mounted on the bar 23 is a channel 25, it in turn slidably receiving a larger channel 26 which is provided with angle brackets 27 and 28 by means of which it may be permanently secured to any convenient support in the refrigerator. The channel 25 at its front end is provided with a laterally extending stop 29 and at its rear end with a stop 30 extending in a direction opposite the stop 29. The middle cross member 12 has secured thereto an angle shaped bracket 31 which as the rack is withdrawn from the refrigerator will strike against the stop 29 thereby withdrawing the channel 25 from channel 26. A sheet metal member 32 is pivotally attached at one end 65 to the channel and has a portion 33 bent un-

derneath and then turned upwardly at its end alongside the opposite side of the channel as shown at 34. As the channel 25 is withdrawn from channel 26 the stop 30 carried thereby will abut against the portion 34 to prevent the complete withdrawal of the channel 25, this operation however, not taking place until the rack has been substantially completely withdrawn from the refrigerator or to such a point that the back 75 20 will close the opening in the refrigerator made by opening the doors 4 or 5 and preventing the escape of the cold air therefrom. It will be noted that the member 32 may be turned to the position indicated in Fig. 11 80 permitting the stop 30 to pass over the portion 34 whereby the rack with the attached guide members 23 and 25 may be disconnected from the refrigerator for cleaning. Ordinarily the inner edge of the portion 34 85 will frictionally engage against channel 26 to retain it in its upper position as shown in Figs. 7 and 10 but by the exertion of slight force said member 32 may be operated to the position shown in Fig. 11. The connection of the channel 26 to the refrigerator may be made in any desired manner, a bracket 35 secured to a side of the provision box being shown in Fig. 3 as a support for said channel and passing around the rack to steady it during its sliding movements.

Various changes and modifications in structure may be resorted to without departing from the invention which is defined in the appended claims. The disclosure made should, accordingly, be considered diagrammatic and illustrative of the invention and not in any sense as limiting it to any certain and precise structure other than required by the said claims.

I claim:—

1. In a refrigerator construction, a rack having sides comprised of spaced apart vertical and horizontal bars, said sides connected together by upper and lower cross members, cross members interposed between the ends of the sides dividing the rack into compartments, spaced apart guide members positioned in horizontal relation in the front compartment and trays carried by said guide members and adapted to be slidably withdrawn from the compartment, substantially as described.

2. In combination, a refrigerator having a front opening therein, a closure for said opening, a rack located back of the opening and mounted to project through the opening, said rack having sides of open formation connected together by spaced apart upper and lower cross members, spaced apart strips secured to the lower cross members and lying lengthwise of the rack, means dividing the rack into front and rear compartments, a plurality of trays slidably mounted one above the other in the front

compartment, and a sheet of continuous material positioned substantially vertically and secured at the rear of the rack, said sheet having dimensions such that it substantially fills the opening in the refrigerator but may pass therethrough, substantially as described.

In testimony whereof I affix my signature in presence of two witnesses.

DANIEL W. TOWER.
